CENTERING DEVICE FOR SWIVEL TRUCKS

William S. H. Hamilton, Larchmont, and Frederic W. Butt, Woodside, Long Island, N. Y., assignors to The New York Central Railroad Company, a corporation of New York

Application May 14, 1936, Serial No. 79,796

24 Claims. (Cl. 105—175)

This invention relates to centering devices for the swivel trucks of locomotives, and particularly to controlling means for governing the action of a swivel truck centering device to regulate and variably govern its action in the travel of the locomotive at different speeds and about curves and along straight portions of a track so as to secure a greater range of flexibility and more efficiently controlled action of the centering device with regard to its degrees of restraining action as required according to varying track conditions and varying speeds of travel of the locomotive.

The spring centering devices commonly employed exert forces tending to hold their swivel trucks in line with the other trucks and resisting swiveling. These forces are adjustable but do not vary with the speed of the locomotive. Such devices, however, if designed with sufficient flexibility for swiveling motion of the swivel truck to allow easy travel of the locomotive about sharp curves at slow speed, at and below, for example, twenty miles per hour, do not offer sufficient resistance against undesirable swiveling or nosing of the truck when the train is traveling on straight or comparatively straight portions of the track at higher speeds and particularly at very high running speeds, when, as a safety measure, nosing should be prevented.

One object of our invention is to provide simple, reliable and efficient means for controlling the centering device of a swivel truck in such a way as to allow free swiveling motion of the truck when traveling about curves at or below a predetermined speed and to give positive restriction to the centering device, with maximum resistance to truck swiveling motion, when traveling at speeds above such predetermined speed, thereby preventing nosing of the locomotive.

A further object of our invention is to provide means for automatically locking the centering device at or above a predetermined speed and releasing it below that speed; when locked, to provide maximum resistance to swiveling movement of the truck and, when released to allow free swiveling movement.

A still further object of the invention is to provide centering means on a swivel truck to cooperate with automatic locking and releasing means therefor on an adjacent rigid truck in such a way that when the automatic device is locked there will be sufficient freedom of swiveling action and of relative movement between the swivel and rigid trucks for easy travel with maximum safety at high speeds; and that when re-

leased there will be enough additional freedom of swiveling action and relative motion of the swivel truck to permit locomotive to pass easily and freely around sharp curves at low speeds.

With these and other objects in view, the invention consists of the features of construction, combination and arrangement of parts, herein-after fully described and claimed, reference being had to the accompanying drawings, in which:

Fig. 1 is a side elevation showing the application of the invention, for exemplification, to a double ended electric locomotive.

Fig. 2 is a diagrammatic plan view showing the general arrangement of the centering devices 15 and their controlling means mounted on the locomotive.

Figs. 3 and 4 are similar views on an enlarged scale of parts of the controlling means.

Figs. 5 and 6 are views, plan and side elevations respectively, on an enlarged scale, of one of the centering devices and a portion of the truck frame on which it is mounted.

Fig. 7 is a section on line 7—7 of Fig. 5.

Figs. 8, 9 and 10 are respectively top plan and side and end elevations showing on an enlarged scale the link latch mechanism and its operating means.

Fig. 11 is a section on line 11—11 of Fig. 8.

Fig. 12 is a view similar to Fig. 8 showing the latch mechanism in link releasing position.

Fig. 13 is an enlarged side elevation of a portion of the rigid truck frame and showing the speed switch drive arrangement.

Fig. 14 is a transverse section taken substantially on line 14—14 of Fig. 13.

Fig. 15 is a view showing a modification.

In the embodiment of our invention as herein disclosed we have shown its application to a double ended type of electric locomotive in which the cab 2 is mounted by center bearings 3 on similar end platforms or underframes 4 having an articulated coupling connection 5 at their inner ends to adapt said platforms to have some relative lateral movement, each platform being mounted on an outer swivel truck 6 and an inner rigid truck 7, the trucks 6 and 7 of each platform section serving respectively as leading or pilot and trailing trucks in the travel of the locomotive in the direction in which the platform mounted on either set of trucks forms the head platform section. The invention, however, may be applied to other types of locomotives or vehicles having swivel trucks, for controlling the swivel truck centering devices thereof; or on lo-

comotives having a different type of truck on which it is desirable to control the relative motion between the trucks.

Mounted upon the inner end of the frame of each swivel truck 6 is a centering device comprising an A-frame 8 the apex of which carries a seat plate 9 having spaced seat recesses 10 and 11. Centrally pivoted to this seat plate, as at 12, is a rocker arm or lever 13 having at opposite sides thereof fulcrum portions 10' and 11' normally engaging said seat recesses in the centered position of said arm or lever. A floating rod or bolt 15 is movable freely through openings in the seat plate 9 and spring cap 17, which in turn is arranged to slide in guide 14 of the frame 8 and is pivoted at its outer end, as at 15', to the rocker lever. Disposed about this rod between spring caps 16 and 17, bearing, respectively, against the outer portion of the frame 8 and in guided relation to the guide 14 thereof, are coiled centering springs 18, the tension of which may be regulated by a securing and tensioning nut 19 on the rod 15, and which springs oppose a resistance to the endwise floating movement of the rod 15 and the rocking movements of the lever 13. The lever 13 is coupled to one end of a controlling link 20, the opposite or free end of which is permitted to slide without restraint or is positively held from movement by the locking and releasing mechanism on the outer end of the adjacent rigid truck frame 7, whereby the action of the centering device is controlled to regulate its degree of resistance to swiveling motion of the truck 6.

The said locking and releasing mechanism comprises a suitable support 21 fixed to the frame 7 and which forms a guide for the free end of the link 20. On the support is mounted a fixed guiding and clamping roller 22 against which one side of the link 20 bears, and pivotally mounted on the support, as at 23, is a clamping lever 24 carrying at one end a guiding and clamping roller 25 bearing against the opposite side of the link, which roller 25 is placed opposite the roller 22 and is movable toward and from the same by reverse swinging movements of the lever 24. In the side of the link facing the roller 22 is a locking notch or recess 26 adapted to be positioned in line with said roller when the centering device is in centered position so that when the notch is in such position and lever 24 is operated to force the roller 25 toward the roller 22 the link 20 will be clamped between the rollers and locked from movement by engagement of the notch 26 with the roller 22. The lever 24 is movable to a sufficient degree in the opposite direction to withdraw the roller 25 to a degree to allow the link 20 to release itself from engagement with the roller 22, while maintaining the rollers 22-25 in position to form guides and retainers allowing the link 20 when released to have limited pivotal movements.

When the link 20 is in the released position the truck can swing freely to the maximum extent allowed by permanent stops, permitting the truck to guide the locomotive freely about sharp curves in the track. Since the link is released at speeds below a predetermined value, for example twenty miles an hour, the locomotive is free to travel about sharp curves at any speed below the predetermined value. We provide a means dependent upon the speed of the locomotive for automatically causing the link locking mechanism to lock or release the link 20; that is, at 75 or below a predetermined speed the centering

device is freed, while at any speed above the predetermined value the link 20 will be locked to allow only a limited range of motion of the centering device, thereby giving maximum elastic resistance to the swing of the truck and not 5 allowing the leading truck to "nose" at high speeds.

The automatic means provided for controlling the locking and releasing mechanism comprises a servo-motor in the form of an air cylinder and 10 piston 27, which piston is coupled to the clamping or locking lever 24 by a connecting rod 28. The motor cylinder is connected, through a feed pipe 29 and an electro-pneumatic control valve 30, with an air supply pipe 31, which is in practice a part of the main reservoir system or other source of compressed air on the locomotive. A hand valve 32 is provided in the pipe whereby the air feed connection may be cut out when desired. The magnet coil 33 of the electro-pneumatic valve 30 is arranged in a conductor 34 normally connected to a supply circuit 35 including a battery switch and fuse block 36 and a battery or other source of electric energy 36', which circuit may form part of the lighting system of the locomotive, and said conductor is adapted to be thrown into and out of connection with the supply circuit by means of a speed controlled switch 37. At all times in the open condition of the switch 37, the pipe 29 is open 20 to the feed pipe 31 through the valve 30, so that air is supplied to the cylinder 27 to hold the locking mechanism in engagement with the control link 20. The switch 37 when closed supplies current to energize the magnet coil 33 35 whereby the valve 30 is moved to open communication between the atmosphere and the cylinder and air is released from the cylinder to retract the locking and releasing mechanism and release the link 20. The switch 37 is open and 40 the valve 30 opens pressure connection to cylinders 27 at all speeds above the predetermined speed, but the switch 37 is closed by its speed controlling mechanism when the speed of the locomotive falls below the predetermined speed, 45 whereupon the coil 33 is energized to cut off the air supply to the motor cylinder for the link releasing action. Thus in the event of any failure in the electrical control part of the apparatus air will be supplied to the motor cylinder 50 to lock the connecting link 20, making it safe to operate the locomotive at high speed.

As stated, the switch 37 is closed at speeds below twenty miles per hour, but opens at higher speeds so that the locking mechanism will always be in action to lock the link 20 in maximum resistance position in the event of failure of the electrical part of the control means to perform its releasing action, and so that the link 20 will be released only in the travel of the locomotive 60 at slow speed. The means for controlling the switch 37 in this manner comprises a gear box 38 secured to the lid or cover of one of the journal boxes on the rigid truck 7, in which box are enclosed gears 39 driven through a suitable connection 40' from the axle journal and coupled by a flexible shaft 40, i. e., a shaft formed of universally jointed sections, with a switch operating device 41 active at speeds above twenty miles per hour to open the switch but inactive at speeds 70 below twenty miles per hour which allows the switch 37 to close again.

A pressure controlled switch 42 may be provided for controlling the supply of current to pilot or signal lamps 43 positioned at opposite 75

ends of the cab. This switch 42 communicates with pipe 29 so as to be normally subjected to air pressure from line 31 to move a switch member 43' against the resistance of a switch closing spring (not shown) forming part of said switch, to connect the lamps 43 with the current supply circuit so long as valve 30 is in position to supply air to the cylinder 27, thus indicating that the electrical control part of the system is working and the system in condition for full control actions. When the switch 37 closes at the speed of the locomotive below the predetermined speed and coil 33 is energized to move valve 30 to air vent position the switch 42 is relieved from air pressure and actuated by its spring to open switch member 43', thus cutting off the supply of current to the lamps 43, indicating that link 20 is in released position and that it is not safe to operate the locomotive at high speeds. Similarly in the event of failure of the electrical part of the system the lamps, through their failure to glow, will give warning of this condition. The current supply circuit may also include an overload circuit breaker 44 of suitable type.

From the foregoing description, taken in connection with the drawings, the construction and mode of operation of our improved means for controlling the centering device of a swiveling truck to regulate its resistance to swiveling movement of the truck will be readily understood without a further and extended description, and it will be seen that the invention provides means for automatically controlling the action of the centering device at speeds below and above a predetermined speed of the locomotive to release the centering device for movement at slow and safe speeds, while locking it from movement at high speeds so that the centering device will exert its maximum restraining action against the swiveling movements of the truck to prevent nosing of the truck at high speeds, so that maximum flexibility of truck action is permitted at slow speeds and safety against undue swiveling or nosing secured at high speeds. Also it will be seen that the invention provides a means whereby, in the event of failure of the means provided for energizing the magnet coil 33 to function from any cause, the centering device will be locked in its maximum restraining position so that the locomotive may be driven at high speeds with absolute safety.

While the construction shown in Figs. 1, 2, 8-12, inclusive, is designed to allow relatively free shifting movements of the link 20 when in released condition, so as to set up practically no restraint to the swiveling of the truck at low speeds, our invention also contemplates the use of means for imposing a desired degree of restraint to the movement of the link from its centered position at low speeds and so that a predetermined force is required to be exerted by link 20 against the sides of recess 26 before movement of link 20 from its centered position can take place. A modified form of the device is shown in Fig. 15 for this purpose. In the modified form of the device illustrated in Fig. 15, which shows the link 20 in released position, inner roller 22 is forced into notch 26 in link 20 by a helical spring 45, the other end of which is carried in a pocket on the rigid truck frame. The characteristics of the notch 26 and the helical spring 45 are such that when swiveling action of swivel truck 6 occurs, roller 22 rolls out of notch 26, further compressing spring 45, before further compression of spring 18 and movement

of lever 13 with respect to seat 9 may take place. Therefore, a restraint is imposed upon the swiveling of truck 6 even in the released condition of the device.

In the locked condition of the device, roller 22 is forced back by the action of air pressure in cylinder 27 and pressure of roller 25 against link 30, until journal pin 47 of roller 22 reaches the inner end of slot 46, in horizontal brackets 21, whereupon a pressure is brought to bear between notch 26 and roller 22 high enough to prevent relative movement between them and the effect is the same as is shown in Fig. 8.

While the structure herein disclosed, and shown for exemplification is preferred, it will, of course, be understood that changes in the form, proportion and details of construction of the parts may be made within the scope of the appended claims, without departing from the spirit or sacrificing any of the advantages of the invention.

What we claim is:—

1. A locomotive having a swivel truck, a centering device controlling the swiveling movements of the truck with respect to the locomotive frame, and automatic means, governed by the speed of the locomotive, for regulating the resistance of the centering device to the swiveling movements of the truck to obtain relatively high and low resistances at locomotive speeds above and below a predetermined locomotive speed.

2. A locomotive having a swivel truck, a centering device governing the swiveling movements of the truck with respect to the locomotive frame, a locking and releasing means for controlling the range of movement of the centering device and its resistance to swiveling movements of the truck at different locomotive speeds above and below a predetermined locomotive speed, and means governed by the speed of the locomotive for controlling said locking and releasing means for locking and releasing actions.

3. A locomotive having a swivel truck, an elastic centering device controlling the swiveling movements of the truck with respect to the locomotive frame, said device including an element lockable for holding the centering device elastically centered and releasable for governing its extent of control motion, and automatic means governed by the speed of the locomotive and operative at different locomotive speeds above and below a predetermined speed for locking and releasing said element.

4. A locomotive having a swivel truck, a rigid truck, a centering device carried by the swivel truck for elastically controlling its swiveling motion and including a control member for regulating its extent of motion, and an automatic train speed controlled locking and releasing means on the rigid truck operative at different locomotive speeds above and below a predetermined locomotive speed for engagement with said control device to hold it in position for maintaining the centering device in centering position or releasing it to permit the centering device to move more or less freely for normal swing of the swivel truck.

5. A locomotive having a swivel truck, a rigid truck, a centering device on the swivel truck for elastically controlling its swinging movements, said centering device including a control element, means on the rigid truck for engagement with said element to hold the centering device in centered position or for releasing said element to permit the centering device to have its normal range of action, and speed controlled means gov-

- erning the first-named means for automatic locking and releasing actions at different locomotive speeds above and below a predetermined locomotive speed.
5. A locomotive having a swivel truck, a centering device for elastically controlling the swinging movements of said truck with respect to the locomotive frame, and speed controlled means governing the centering device to permit the 10 same to have its normal range of movement and elastic resistance to swinging movements of the truck at a predetermined slow speed of the locomotive and for locking the resistance device in maximum resistance position at higher speeds of 15 the locomotive.
7. A locomotive having a swivel truck, a centering device for elastically controlling the oscillations of the truck with respect to the locomotive frame, a locking and releasing arm connected with the centering device whereby its 20 controlling actions may be controlled, and means governed by locomotive speeds for automatically locking and releasing said arm at locomotive speeds above and below a predetermined speed.
8. A locomotive having a swivel truck, a rigid truck, a centering device on the swivel truck including a centering spring and a lever mechanism through which the resistance of the spring is transmitted to said truck, a connecting link for 25 connecting said lever with and disconnecting it from the rigid truck, locking means on the rigid truck cooperating with said link for effecting such connection and disconnection, and means governed by locomotive speed for throwing said 30 locking means into and out of action at different locomotive speeds above and below a predetermined locomotive speed.
9. A locomotive having a swivel truck, a rigid truck, a centering device on the swivel truck including a centering spring and a lever mechanism through which the resistance of the spring is transmitted to said truck, a connecting link for connecting said lever with and disconnecting it from the rigid truck, means on the rigid truck 35 normally engaging and locking said link to maintain the centering device in maximum resistance position, and speed controlled means controlling said locking means to lock said link in such controlling position at and above a predetermined 40 locomotive speed and to release said link to permit normal movements of the centering device at slower locomotive speeds.
10. A locomotive having a swivel truck, a rigid truck, a centering device on the swivel truck including a centering spring and a lever mechanism through which the resistance of the spring is transmitted to said truck, a connecting link for connecting said lever with and disconnecting it from the rigid truck, locking means on the 45 rigid truck normally engaging the link to hold the centering device in maximum resistance position, and locomotive speed controlled means for releasing said locking device at a predetermined slow locomotive speed without affecting its locking 50 action at higher locomotive speeds.
11. A locomotive having a swivel truck, a centering device for opposing an elastic resistance to the swiveling movements of the truck, a device for locking said centering device in its position for establishing a maximum resistance to the 55 swiveling movements of the truck or releasing it for normal resistance actions, actuating means for the locking device normally effective for maintaining the locking device in action at all locomotive speeds, and means effective for influencing 60
- said actuating means at predetermined slow speeds of the locomotive to release said locking device and ineffective for such action at higher locomotive speeds.
12. A locomotive having a swivel truck, a rigid truck, a centering device on the swivel truck for opposing an elastic resistance to the swiveling movements of said truck, a coupling member associated with the centering device, a device on the rigid truck for coaction with said coupling member for locking the centering device in its position for establishing a maximum resistance to the lateral movements of the swivel truck or releasing it for normal resistance actions, actuating means for the locking device normally effective for maintaining the locking device in action at all locomotive speeds, and means effective for influencing said actuating means at predetermined slow speeds of the locomotive to release said locking device and ineffective for such action at higher locomotive speeds.
13. A locomotive having a swivel truck, a centering device for opposing a variable elastic resistance to the swiveling movements of the truck, a locking device for connecting the centering device with or disconnecting it from a part of the locomotive with relation to which the swivel truck swivels for holding said centering device in its maximum resistance position or releasing it for normal resistance actions, pneumatic means 25 for normally maintaining the locking device in locking position, electrical control means effective for action on said pneumatic means when set into action to release the locking means, and locomotive speed governed means operative on 30 said electrical control means to release the locking device at predetermined slow locomotive speeds but ineffective for such action at higher locomotive speeds.
14. A locomotive with two swivel trucks in which a device is used for holding them in one elastic relation with each other above a predetermined speed and a different elastic relation below said predetermined speed.
15. A locomotive having trucks mounted for relative swiveling movements, a centering device including locking and releasing means for holding the trucks in one elastic relation when running above a predetermined speed, and means acting in the released condition of the locking means for holding the trucks in a different elastic relation 40 below said predetermined speed.
16. A locomotive having trucks mounted for relative swiveling movements, a centering device on one of the trucks, a speed controlled locking device on the other truck, a shiftable coupling link connected to the centering device and adapted to be locked against movement at predetermined high train speeds and released for movement at lower train speeds to control the action of the centering device, and means acting in the released condition of the link to maintain it in engagement with the locking device and allow of its release therefrom under a predetermined force.
17. A locomotive with two relatively swiveled trucks in which a train speed controlled device is used for holding them in one elastic relation with each other above a predetermined speed and a different elastic relation below said predetermined speed.
18. A locomotive having a truck mounted to oscillate with respect to the locomotive frame, and a device for holding the truck in a predetermined elastic relationship with respect to the frame above a predetermined speed and in a different 70

- elastic relationship with respect to the frame at a speed below said predetermined speed.
19. The combination with a locomotive having oscillating trucks, of means for establishing an elastic resistance to oscillation of the trucks with respect to the locomotive frame, and means dependent on the locomotive speed and controlling the elastic resistance means to vary its elastic resistance to oscillation of the trucks at different locomotive speeds with respect to a predetermined intermediate locomotive speed.
20. The combination with a locomotive having oscillating trucks, of means for establishing an elastic resistance to oscillation of the trucks with respect to the locomotive frame, and speed controlled electro-pneumatic means controlling the elastic resistance means to vary its elastic resistance to oscillation of the trucks at different locomotive speeds above and below a predetermined locomotive speed.
21. A locomotive having a swivel truck, a restraining device for elastically controlling the oscillations of the truck, and automatic speed controlled locking and releasing means for action on said restraining device to vary its elastic resistance at different locomotive speeds above and below a predetermined speed to the oscillations of the truck.
22. A locomotive having a swivel truck, a rigid truck, a restraining device for elastically controlling the oscillations of the swivel truck, and automatic speed controlled locking and releasing means carried by the rigid truck for action on said restraining device to regulate its elastic resistance at different locomotive speeds above and below a predetermined speed to the oscillations of the swivel truck.
23. In a railway vehicle, the combination with an underframe structure and trucks swiveled with relation thereto to swing laterally thereof, of vehicle speed controlled elastic restraint means carried by the vehicle and acting on said swiveled trucks for opposing a yielding resistance to the swinging movements of said trucks at and above a predetermined vehicle speed.
24. In a railway vehicle, the combination with a vehicle body supporting frame, and a pair of trucks arranged adjacent to each other and one swiveled relative to the other, of elastic restraining means for opposing a yielding resistance to the relative swiveling movements of the trucks at and above a predetermined vehicle speed, and speed controlled means governing the restraining actions of the restraining means.

WILLIAM S. H. HAMILTON.
FREDERIC W. BUTT.
